CLAIM

The ornamental design for a battery pack terminal and housing, as shown and described.

DESCRIPTION

FIG. 1 is a front perspective view of a battery pack terminal and housing showing my new design.

FIG. 2 is a front elevational view thereof.

FIG. 3 is a top plan view thereof.

FIG. 4 is a right side view thereof; and,

FIG. 5 is a left side elevational view thereof.

The broken line showing is for illustrative purposes only and forms no part of the claimed design.
